UNITED STATES PATENT OFFICE.

EDGAR E. ABRAHAMS, OF DORCHESTER, MASSACHUSETTS.

FOLDING DISPLAYING-EASEL.

1,272,349.

Specification of Letters Patent. Patented July 16, 1918.

Application filed June 24, 1916. Serial No. 105,627.

To all whom it may concern:

Be it known that I, EDGAR E. ABRAHAMS, a citizen of the United States, residing at Dorchester, in the county of Suffolk and 5 State of Massachusetts, have invented an Improvement in Folding Displaying-Easels, of which the following description, in connection with the accompanying two sheets of drawings, is a specification.

10 This invention has for its object the production of a novel and attractive displaying easel, of the folding type, which is intended to be used more particularly for advertising purposes and can be made up from but two 15 individual parts disengagingly interlocked and coupled together to form a unit, without incorporating in the design thereof the use of glued joints, ordinarily depended upon in other makes of easels of this type.

20 The use of glued joints in easel work has always been objectionable, because of the complications arising therefrom and the consequent increase in the cost of manufacture, as well as on account of diminishing the degree 25 of foldability of the same, and negativing the extent and possibility of applying printed or painted matter on the exposed surfaces thereof for advertising purposes, before the cutting operation; since it is a known fact that the gluing process interferes 30 with whatever printed or painted matter appears thereon, and often results in spoiling the same; while to otherwise print on the same, by machine, after the gluing process 35 has taken place (either before or after the folding and setting up of the easel) has been proven to be absolutely impracticable for reasons which must appear obvious to persons familiar with the art of making 40 easels.

To provide a simple and inexpensive displaying easel which may be used especially for advertising purposes, and in which the articles advertised may be displayed to advantage and surrounded with attractive and suitable advertising or descriptive matter which may be printed, embossed, or painted on the easel itself and yet will permit the same to be foldable and readily set up, is 45 the purpose of my invention.

Referring to the drawings—

Figure 1 represents a development of the two parts making up the easel, showing both parts laid out on a single sheet of cardboard, 55 or other suitable material.

Fig. 2 represents a perspective view of the easel set up in working position.

Fig. 3 represents an end elevation of the easel.

Fig. 4 represents a plan view of the easel. 60

Fig. 5 represents a perspective view showing the rear of the easel.

Fig. 6 represents a front elevation of the easel, the horizontally dotted lines indicating retaining tabs which may be provided 65 on the lower and upper edges of the displaced opening in the easel.

Fig. 7 represents a sectional view taken on line 7—7, Fig. 6.

Fig. 8 represents a sectional view taken on 70 line 8—8 in Fig. 6.

Fig. 9 represents a sectional view taken on line 9—9 in Fig. 6.

Fig. 10 represents a similar view to that shown in Fig. 9 but shows the top of the container closed in and the displaced opening provided with the longitudinal retaining tabs represented by the dotted lines in Fig. 6. 75

Fig. 11 represents a rear view of a supporting end of the easel. 80

Fig. 12 represents a front elevation of the easel with the container-member removed therefrom (being a modification), showing a lattice member provided across the displaced opening of the easel. 85

Like numerals refer to like parts throughout the several views of the drawings.

The numeral 1 represents a flat sheet of card-board, fiber, metal, or other suitable material, from which the standard-member 90 2 and the container-member 3, which make up the easel, are cut; the standard-member 2 being designed with the displaced-opening 4, which is preferably provided with the vertical retaining-tabs 5 and the container-

locking-slots 6. 7 represents the container-bottom-flap which is preferably provided with the supporting-tabs 8 and is creased at 9 and made integral with the standard-member 2 of the easel. 10 represents the easel 100 standards provided on the ends of the easel-member 2, which standards are made integral therewith and creased at 11 and are each provided with the longitudinal locking-slots 12. 13 represents a combined easel-

brace and standard-locking-member which is made integral with the standard-member 2 and creased at 14 and provided with the end locking-tabs 15 which are also preferably creased at 16 and provided with the 105 110

locking-tongues 17 for engaging with the slots 12 provided in the standards 10 of the easel-member 2 therefor. 18 represents the rear wall member of the container-member 3 which is provided with the longitudinal supporting-slots 19, into which are fitted the supporting-tabs 8 of the easel-standard-member 2, when the container-member 3 is associated and coupled therewith, as shown in Fig. 2. 20 represents the side flaps of the container-member 3 which are of a width equal to the depth of the container-bottom 7, and are made integral with the container-back 18 and creased at 21, and are provided with the lower and upper locking-tongues 22 which fit within the locking-slots 6 provided therefor in the easel-standard-member 2 to couple and secure said container-member 3 with said standard-member 2. 23 represents expansion-slots which are provided in the container-sides 20 for permitting the proper interlocking of the locking-tongues 22 with the slots 6 provided in the easel-standard-member 2. 25 23^a represents a middle locking-slot which may be used in place of the other two slots 23 shown on the container-sides 20, when desired. 5^a represents the longitudinal retaining flaps provided in the displaced openings 4 of the easel-standard-member 2, as shown in Figs. 1, 6 and 10. 7^a represents a container top which is made similar to the container-bottom 7 and may be made integral with the standard-member 2 and creased at 35 9^a, being also provided with supporting-tabs 8^a which may be secured in a similar manner to the upper supporting-slots 19^a provided in the container-member 3 for the purpose, when a top for the container is desired, as shown in Fig. 10. 40 2^a in Fig. 12 represents a modified easel-stand which is provided with the lattice-strip 24 for dividing up the displaced opening 4^a,—it being understood that one or 45 more of such lattices may be used to equal advantage across the displaced opening of the easel.

Having thus described the parts of my invention in detail, the manner in which the same may be constructed and set-up, is as follows:

The development of the standard-member 2 and the container-member 3 may be preferably laid out on the same piece of stock 1 and scored and cut out by the proper cutting devices in a single operation, after which operation the two parts of the easel are left ready to be properly folded and coupled together,—it being here noted that 55 the easel may be tipped and supported (when set up) in any desired angle by providing the proper angle of slant on the supporting edges 25 of the standards 10. The standards 10 may be creased back into position on the lines 11. The brace member

13 is also creased back on line 14, and the locking-tongues 17 are brought into engagement with the locking-slots 12 of the standards 10. The container-bottom 7 is next creased back on line 9, when the easel-standard 2 becomes erected and ready to receive the container-member 3. The sides 20 of the container-member 3 are next creased and folded back on the lines 21 at practically right angles with the back 18 of the container-member 3. The locking-tongues 22 are then brought into working engagement with the locking-slots 6 of the easel-standard-member 2, and the supporting-tabs 8 of the standard-member 2 are inserted within the supporting-slots 19 of the container-member 3. With the container-member thus associated with the standard-member 2, the easel is complete and ready to receive the article or articles to be displayed therein,—it being understood that any desired form of decorations or advertising matter may be printed, embossed, or otherwise suitably applied on the exposed surfaces of said easel (especially the front surface of the easel which contains the displaced opening 4) before the cutting operation occurs, or after said operation, but before folding, if desired, according as may be most convenient.

It may be observed that the easel may be made up of any desired contour which will tend to make the same artistic looking and attractive, and when set up in working operation will take up the least base room possible,—the easel being composed of two simple parts which may be shipped and packed flat and readily folded and set up without the use of glue, or any other such adhesives or similar substances used ordinarily for joining parts together. Also, the construction of the easel, as herein disclosed, will permit of the supporting of appreciably heavy wares or articles therein, as for example, filled candy boxes and the like, displayingly supporting the same and attachably securing the same therein.

It may further be observed that for displaying smaller articles, a pane of glass, or sheet of isinglass or like material, about the size of the displaced opening, may be inserted in the rear of the retaining-tabs, and will show up the articles without permitting access thereto from the front of the easel;—access being had thereto through the open top of the container if desired.

Also, it may be observed that the stock, from which the easels are to be cut, when made of card or fiber board, or the like, may have whatever printing matter is to be applied thereto printed thereon within the borders of the easel parts before the cutting operation occurs, since neither the latter operation nor the folding and setting up operation of the easel will in any way inter-

fere with or injure said printed matter, as would most likely be the case in the event that the easel parts were to be joined together by the use of adhesives instead of 5 the interlocking joints used in the same.

Again, it may be observed that the expansion-slots, 23 or 23^a used on the engaging sides 20 of the container-member 3, permit of associating and locking the latter 10 member 3 readily with the standard-member 2 of the easel, and exert every tendency to keep the two locked in working relationship with each other through the expansion feature provided thereby, which acts upon 15 the locking-tongues 22 and forces them into, and holds them set in their respective locking-slots 6 against coming out and becoming uncoupled therefrom.

While the preferred embodiments of my 20 invention have been described in detail, it will be understood that I do not wish to be limited to the particular construction set forth, since various changes in the form, material, proportions, and arrangement of 25 parts and in the details of construction may be resorted to without departing from the spirit and scope of the invention, or destroying any of the advantages contained

in the same, heretofore described and defined in the subjoined claim.

30

What I claim is:

An article of manufacture, consisting of a front panel-member, provided with a display opening having retaining-tabs and locking-slots, side supporting brackets integral with said panel member and foldable therewith, and provided with locking-slots; a foldable brace member integral with 35 said panel-member and foldable therewith at the bottom thereof, and provided with 40 locking-tongues adapted to engage with the locking-slots in said side supporting brackets; a container-flap provided with supporting-tabs, a container member provided with supporting-slots adapted to receive 45 said supporting-tabs of said container-flap, side members made integral with said container-member and foldable therewith, and provided with locking-tongues and expansion-slots adapted to engage said container-member with said panel-member, substantially as shown.
